POWER LAWN MOWER

Eliad A. Bovee, Lansing, Mich., assignor to Motor Wheel Corporation, Lansing, Mich., a corporation of Michigan

Application December 27, 1954, Serial No. 33,682

Term of patent 14 years

(Cl. D40—1)

FIG. 2

FIG. 1

FIG. 3

Fig. 1 is a perspective view of a power lawn mower, showing my new design, the power unit, handle, and wheels being shown in dotted lines.

Fig. 2 is a front elevation.

Fig. 3 is a plan view.

The characteristic features of the design reside in the housing shown in full lines.

I claim:

The ornamental design for a power lawn mower, as shown and described.
